UNITED STATES PATENT OFFICE.

EDGAR F. HATHAWAY, OF BOSTON, MASSACHUSETTS.

STRIP-SERVING DEVICE.

1,235,566.

Specification of Letters Patent. Patented Aug. 7, 1917.

Application filed September 23, 1912. Serial No. 721,792.

To all whom it may concern:

Be it known that I, EDGAR F. HATHAWAY, a citizen of the United States, and a resident of Boston, in the county of Suffolk and 5 State of Massachusetts, have invented an Improvement in Strip-Serving Devices, of which the following description, in connection with the accompanying drawings, is a specification, like characters on the drawings representing like parts.

This invention relates to strip serving devices.

In order that the invention may readily be understood, I have disclosed a single embodiment thereof in the accompanying drawing, wherein—

Figure 1 is a vertical longitudinal section of a strip serving device embodying my invention;

20 Fig. 2 is a plan view thereof; and

Fig. 3 is a detail representing different positions of the strip severing instrumentality.

The strip serving device embodying my 25 invention is intended for general application, and an important object of the invention is to provide a structure of commercially acceptable but simple form and composed of but few parts.

30 In the practice of the invention, I employ a suitable strip package, preferably formed as a roll of paper or other suitable material, such as cloth. This strip roll may have an adhesive previously applied to one 35 of its surfaces, and the surface so treated may be drawn or fed in contact with a strip moistener. Within the scope of the invention, however, a suitable strip having no adhesive applied thereto may be drawn or fed

40 in contact with an adhesive applying device. Preferably, however, I employ a previously gummed paper or like strip, and have herein represented the strip as gummed on its outer surface. In other words, the 45 strip roll is represented as wound with its gummed surface outward, though my invention is not limited in this respect.

Referring more particularly to the drawings, the strip roll support is herein represented at 1, it being preferably an integral metallic cast structure having a base 2 and a chambered strip roll receiving extension 3, upstanding therefrom, as clearly represented in Fig. 1. If desired, the base 2 may 55 be provided with bolt holes 4 or other suitable provisions for securing the device to

a table or other suitable support. Separating the base 2 from the chambered extension 3 is a web or partition 5 preferably integral with the base and extension. This 60 web or partition constitutes the base or support for the strip roll 6 and is made inclined, so that as the strip roll diminishes in diameter during use, the said roll may be held and centered. Preferably this partition 65 5 is provided with converging surfaces 7—7 forming a V-shaped support for the purpose stated.

The strip is rendered adhesive either by the use of water in case the strip has been 70 previously gummed, or by the use of some suitable adhesive liquid, such as a paste or glue, to be applied to the ungummed strip. In either case I preferably provide a tank or reservoir 8 in operative relation to the 75 service path of the strip, and have herein represented the same as integral with the base 2 and in advance of and below the service path of the strip. The position of said tank or reservoir, if employed, may, however, be varied within the scope of the invention. In order to provide for a large 80 chamber for the reception of the water preferably employed as a moistening liquid, the tank or reservoir 8 is placed in communication with the chamber 9 beneath the web or partition 5, this being effected by terminating the wall 10 at a suitable point above the base 2. It will, of course, be understood 85 that the chamber 9 is provided with inclosing walls upstanding from and preferably integral with the base 2.

For simplicity of description, I will assume that the strip is previously gummed and that water is employed to moisten the 90 same, this being in accordance with the preferred commercial use of the invention. To apply the water to the gummed face of the strip, I preferably employ a rotatable moistener 11 represented as a drum or 100 roller having an axle 12 supported in bearings 13 in the side walls of the tank 8. Preferably this moistener is wholly metallic, the metallic periphery 14 thereof being employed to convey water to the strip. I have 105 ascertained in the course of my experiments that a much better supply of water may be lifted from the tank and carried against the strip by suitably recessing the peripheral surface of the roller 11. While these recesses 110 may be of any suitable form, I have secured the best results by providing said surface

with peripheral grooves 15, herein represented as a spiral or screw thread. The said grooves constitute fluid conveying depressions which in practice convey a satisfactory supply of water to the strip.

Preferably the strip is served by draft thereon by the operator who seizes the strip between the thumb and fingers of one hand and draws the strip outwardly in contact with the moistener substantially as represented in Fig. 1. In order to sever the strip, I provide a suitable strip severing instrumentality, preferably so arranged that the strip is moved, and in this form of the invention is lifted thereagainst. Difficulty has heretofore been experienced in severing the strip accurately, because when the strip is drawn against the severing instrumentality the strip is apt to slip more or less,—that is, to be drawn farther forward,—during the strip severing operation. In order to overcome this difficulty, I have provided strip holding means preferably embodied in strip binding or clamping means. This strip holding or binding means is preferably rendered effective by relative movement of the strip and the severing instrumentality. In the disclosed embodiment of the invention, the strip is moved by the operator toward the severing instrumentality, and this movement results in the automatic binding or holding of the strip against slipping during the severing operation. This result is preferably effected by employing a resilient member 16 herein formed of bent metal and secured to the front of the casing or support 1 by means of a bent metal member 17, which also constitutes a latch or securing means for the door or closure 18. This door or closure is represented as hinged at 19 to the rear of the support in any suitable manner. Preferably it is provided with two split or bent pins 20 which are in vertical alinement and inserted in vertical holes in ears extending from the door and from the support or base.

The resilient member 16 is represented as bent into general U-shape, and substantially at its bend it engages the upper surface of the strip as represented at 21 and presses the same against the forward inclined surface 7, which also constitutes a strip receiving and guiding surface along and in contact with which the strip passes from the strip roll to a point adjacent the moistener roller 11.

The upper end of the resilient member 16 is preferably bent as indicated at 22, and is provided with a cutting edge 23 against which the strip is drawn for severance. Owing to the resilience of the member 16, while the strip is being drawn from the strip roll and in contact with the moistener, as represented in Fig. 1, the bent por-

tion of the resilient member 16 bears thereon, but not with sufficient force to bind or hold the strip. When, however, the strip is drawn or lifted upward against the severing edge 23 for severance, this action results in the slight upward yielding of the severing edge and hence in the flexure and forward movement of the resilient member 16 from its point of attachment to the structure. This results in the holding, binding or clamping of the strip by said resilient member against the strip guiding surface 7, and prevents all slipping of the strip during the severing operation. This action is indicated diagrammatically in full and dotted lines in Fig. 3.

The means herein shown for holding or binding the strip is preferably employed, but I am not limited thereto in all aspects and embodiments of my invention, since changes therein within the scope of the claims may be made.

It will be observed that the guiding surface 7 is so inclined that it provides an inclined path of movement for the strip, which, if extended forward beyond said surface, would pass substantially above the surface of the moistener. In other words, the said inclined surface 7 directs the strip to a point substantially above the moistener, so that after strip severance, the tendency of the strip is to remain in its inclined path. The member 16 by retaining the strip flatwise against the strip guiding surface 7 during the entire serving operation, effects an easier and more even and smooth feeding of the strip than would be the case if the strip were periodically lifted from such surface. The construction is a compact one and particularly co-operates with the positioning of the moistener in advance of such surface and substantially in the position shown.

It will be observed that the disclosed embodiment of the invention is of exceedingly simple structure and as herein represented consists of three castings, one being the base with its chambered extension, the second being the door or closure therefor and the third being the moistener roller. In addition to these parts, there are herein employed merely the severing member 16 and its securing means constituting also a latch for the door, together with the split pins serving as pintles for the door.

It will be observed that in this, the preferred form of the invention, the strip roll is not supported by an axle, but rests by its own weight upon the inclined supporting surfaces 7—7.

Having thus described one illustrative embodiment of my invention, I desire it to be understood that although specific terms are employed, they are used in a generic and descriptive sense and not for purposes of lim-

itation, the scope of the invention being set forth in the following claims.

Claims:

1. A strip serving device consisting of a strip support, means for rendering the strip adhesive, strip severing means and a spring member constructed and arranged to engage the strip during the serving action and to bind or clamp the strip during the severing action, said severing means and spring member being operatively connected to cause flexure and consequent binding action of the spring member by the engagement of the strip and the severing means in the strip severing action.
2. A strip serving device consisting of a strip support, means for rendering the strip adhesive, strip severing means, and a spring member co-acting with said strip severing means and constructed and arranged to engage the strip during the serving action and to be flexed by movement of the strip into severing position to bind the strip during the severing action.
3. A strip serving device consisting of a strip support, means for rendering the strip adhesive, strip severing means, and a spring member operatively connected to the strip severing means and constructed and arranged to be flexed by relative movement of the strip and severing means, thereby to impart pressure to the strip during the severing action, and to hold the strip by said relative movement of the strip and severing means.
4. A strip serving device comprising a strip support, means for rendering the strip adhesive, and a resilient member constituting strip severing means and strip binding means and constructed and arranged to engage the strip during the serving operation and to be flexed into binding relation with the strip in the strip severing operation.
5. A strip serving device provided with a resilient member having a strip severing edge, said resilient member being bowed and mounted to engage the strip and to be flexed, and thereby to bind the strip upon deflection of the strip severing edge incident to the severing action, said device having a surface with which said resilient member co-acts to bind the strip.
6. A strip serving device having a strip guiding surface, and a resilient member engaging the strip while on said guiding surface and adapted to be flexed to bind the strip against said surface, said resilient member being provided with a strip severing edge.
7. A strip serving device consisting of a base having a reservoir and a moisture applying means and a chambered strip roll support having an upwardly inclined strip guiding path extending to a point slightly in the rear of and slightly below said moisture applying means, means to hold the strip at all times against said guiding path, means to bind the strip against movement along said path during the severing action and a severing blade directly over and adjacent to said moisture applying means, said severing blade and strip holding means being operatively connected and said strip holding means being moved by strip deflection for severance to bind the strip against said path.
8. A strip serving device consisting of a base having a chambered strip support upstanding therefrom and integral therewith and also having a tank or reservoir integral therewith, a closure for said chamber, a rotatable moistener supported by said tank or reservoir, a bent metal member having a strip severing edge, and a bent metal member for securing said first member in position and for securing said closure.
9. A strip serving device comprising in combination a strip roll support having a moistener in operative relation to the service path of the strip, said support having an upwardly inclined continuous guiding surface directing the strip to a point substantially above the moistener, strip severing means and means positively to force the strip at all times against said guiding surface and to bind it thereagainst during the severing action, said strip severing means and strip forcing means being operatively connected to effect the binding action on the strip during the severing action.
10. A strip serving device having strip supporting surface 7, a moistener 11 in advance thereof, a housing for the strip, and a resilient member 16 secured to the housing and having a severing edge 23 positioned above the moistener and against which the strip is adapted to be deflected for severance, said resilient member 16 being positioned to engage the strip upon the guiding surface 7 and to bind the same thereagainst during the severing action.

In testimony whereof, I have signed my name to this specification in the presence of two subscribing witnesses.
